CLAIM

The ornamental design for a tooth brush, as shown and described.

DESCRIPTION

FIG. 1 is a left side elevational view of the tooth brush showing my design;

FIG. 2 is a right side elevational view thereof;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a front perspective view thereof.

The stippling represents a matte surface treatment.
